UNITED STATES PATENT OFFICE.

CLARE H. DRAPER, OF HOPEDALE, MASSACHUSETTS, ASSIGNOR TO DRAPER COMPANY, OF HOPEDALE, MASSACHUSETTS, A CORPORATION OF MAINE.

STEEL-HARNESS MOTION FOR LOOMS.

SPECIFICATION forming part of Letters Patent No. 744,910, dated November 24, 1903.

Application filed July 31, 1903. Serial No. 167,668. (No model.)

To all whom it may concern:

Be it known that I, CLARE H. DRAPER, a citizen of the United States, and a resident of Hopedale, county of Worcester, State of Massachusetts, have invented an Improvement in Steel-Harness Motion for Looms, of which the following description, in connection with the accompanying drawings, is a specification, like letters on the drawings representing like parts.

This invention relates particularly to harness or shedding motion for looms wherein the so-called "steel harness" is employed, such term being technically applied to harnesses of the type wherein the heddles are made of thin flat metallic strips longitudinally slotted to receive a supporting-bar of less depth than the length of the slots, the heddles also acting as warp-stop-motion controlling-detectors. Such form of harness is shown in United States Patents Nos. 536,968 and 536,969 and in others, which are well known to those skilled in the art.

It is a fact well known to those familiar with the practical operation of both types of loom-harness that cloth can be woven with a slackener tension when "cotton harnesses" are used than when the regular or usual form of stop-motion steel harness is employed. There are also certain goods requiring a "face" or surface appearance which can now be made only with the cotton harness.

My present invention has for its main object the production of means to overcome these disadvantages of the steel-harness motion, as well as to prevent warp breaks and slack threads to some extent by eliminating a good deal of the strain on the warp. The action of the cotton harness differs from that of the steel harness in several important respects. The warp-eyes of the former are always at a fixed distance from the top of the harness-frame, so that necessarily the warp follows the exact motion imparted by the shedding-cam. On the other hand, in the steel harness the heddle hangs upon or is suspended from the heddle-bar when its frame is up, and it presses up on the bar when the frame is down. Consequently when the frame is up the warp-eye of the heddle is lower with respect to the bar than when the frame is

down, and at some point intermediate the extreme positions the bar is midway in the slot of the heddle. At that point the warp-thread passing through the warp-eye of the heddle is not being either raised or lowered by the action of the shedding-cam. In other words, it is not then "controlled" by such cam. Should the lay beat up at this point, it is not at all certain that all of the threads will be held at the same height, and if not their tension will not be uniform and the appearance of the cloth is apt to suffer. On account of the lack of control of the heddles referred to the momentum of the latter, both in the rise and fall, must be stopped by their several warp-threads, resulting in straining the latter. Inasmuch as the heddle-bar of a steel harness traverses the heddle-slot in addition to moving the warp the proper distance it is manifest that it goes farther than a cotton-harness frame for the same shed opening, and if the time of motion is the same (as it must be when the same dwell is used) the motion is quicker and gives more jerk to the warp-threads.

In accordance with my present invention the heddles are so mounted that the various objections and disadvantages heretofore mentioned as now attendant upon the use of steel harness are either wholly eliminated or reduced to such a minimum as to cease to be objectionable in practice.

The various novel features of my invention will be fully described in the subjoined specification, and particularly pointed out in the following claims.

Figure 1 is a front elevation, centrally broken out, of a sufficient portion of a steel-harness motion to be understood with one embodiment of my present invention applied thereto. Fig. 2 is a vertical sectional detail on the line 2-2, Fig. 1, looking toward the right. Fig. 3 is a left-hand side elevation of the loom-frame and harness-motion, the nearer side of the frame being broken off to show clearly the parts beyond it. Fig. 4 is an enlarged side elevation of one of the shedding-cams shown in Fig. 3. Fig. 5 is a detail of the portion of the stop-motion mechanism intermediate the feelers and the shipper knock-off lever, omitted in Fig. 3 to avoid confusion.

Fig. 6 is an enlarged front elevation of one of the upper corners of a harness-frame with several heddles mounted thereon viewed in the relative position of the parts when the frame is up. Fig. 7 is a vertical sectional view thereof on the line 7 7, Fig. 6, looking toward the left. Fig. 8 is a sectional view on line 8 9, Fig. 6, looking toward the left, taken when the harness-frame is up. Fig. 9 is a similar view on the same line 8 9, but taken when the frame is down. Fig. 10 is a side elevation of one of the heddles detached, and Fig. 11 is a perspective detail of the holding device for the movable heddle-bar.

In Figs. 1 and 3 I have shown my present invention in connection with harness-actuating mechanism, substantially as shown and described in United States Patent No. 733,089; but my invention is not restricted thereto, as any other suitable form of actuating mechanism may be used in lieu thereof.

The loom-frame A, arch A^X, the shipper S^X, and its notched holding-plate N, Fig. 3, the cam-shaft C^X, the treadles T and T' each having a roll, as t^X, to coöperate with its particular cam, the latter being shown at C and C' for a two-harness set in the present embodiment of my invention may be and are of substantially well-known construction.

The pair of oppositely-rocking bell-cranks m' m² and n' n² for each harness-frame, fulcrumed at a' and a², respectively, and connected by an equalizing-link e, the lifting-spring S, connecting the upturned arms of each pair of bell-cranks, and the depending links 10 12, connecting the latter with the top of the harness-frame, are all substantially as in Patent No. 733,089 and operate as therein provided for, the treadles being connected with the bottoms of the harness-frames by adjustable connectors t and t' of well-known character.

The harness-frames comprise each a suitable bottom bar h, upright side bars h', (shown as rods rigidly attached thereto,) and at their upper ends screwed or otherwise rigidly secured to depending bosses h³ of heads h³, and the latter are rigidly connected by an upper cross bar or bars h^X, corresponding to the usual heddle bar or support in a steel harness.

Inasmuch as the two frames herein illustrated have the same construction only one will be described in detail; but in Figs. 1 and 3 I have indicated the front and back frames as H and H', respectively.

As most clearly shown in Figs. 7, 8, and 9, each frame is provided with two bars h^X to support each a bank or series of heddles d, which are also warp-stop-motion controlling-detectors, the heads h³ having oppositely-located seats 15 (see Fig. 7) to receive the ends of the bars, which are notched at 16, Fig. 6, to receive the shank of a holding-bolt 17. 65 This bolt passes through a vertical slot h⁴ in the head, so that by loosening the nut 18 the bolt can be slid upward to release the heddle

bar or bars. The heads are flattened above the bosses h³ and are each surmounted by an eye h⁵ for the reception of the lower end of the suspending-link, while an ear h⁶, having a vertical hole h⁷ through it, is extended outward from each head near its top for a purpose to be described. A plunger e is adapted to slide vertically in each ear h⁶, the lower end of the plunger being provided with an enlarged base e^X, having depending parallel portions e' and a central tongue-like part e², leaving a clearance between it and each of the outer portions e', as best shown in Fig. 11. 80 The base is located outside the head, (see Fig. 6,) with its depending side portions e' parallel to the front and rear faces of the head, the tongue e² being of slightly greater thickness than the head.

A pair of auxiliary heddle-bars h^X are mounted on each harness-frame, as herein shown, the said auxiliary bars having their ends inserted between the sides e' and the tongue e² of each plunger-base and held in 90 place by a cotter-pin or other suitable fastening 20, passed through holes in the several parts. The tongue separates the two bars h^X, so as to admit the head h³ between them without binding thereupon, so that the bars may 95 move upon the head in a vertical direction toward and from the fixedly-attached main heddle-bars h^X. A spiral spring s^X is interposed between each ear h⁶ and the plunger-base e^X, surrounding and normally tending to 100 depress the plunger.

The heddles d are made of thin flat metallic strips each having a warp-eye, as 2, and longitudinally slotted at its upper end at d', the general structure of the heddle being well known; but the slot d' is made of greater length in my present invention, as each heddle is controlled by two heddle-bars—that is, the main bar h^X and the corresponding auxiliary bar h^X are both extended through the 110 slots of a bank of heddles, as clearly shown in Figs. 6, 8, and 9, the plunger-springs s^X acting in such manner that while the two bars of a bank of heddles are held apart the warp-eyes 2 will be at a constant distance from the 115 main or upper bar h^X, which latter is accurately controlled by the shedding-cam. Such separation of the bars is maintained during the motion for shedding, as will appear hereinafter.

A transversely-extended casting g, having openings g^X (see Fig. 1) for the passage of the lay-pitmen, is bolted to the loom-frame, the central portion of the casting being interposed between the lower ends of the heddles 125 of the front and rear frames and forming a back-stop or support for a released heddle when engaged by a feeler in well-known manner.

End guards or stops g', Fig. 1, are mounted 130 on the back-stop at the ends of the banks of heddles to guide and prevent them from moving outward too far.

The casting g has depending hangers g² near

its ends to provide bearings for two parallel rock-shafts f^x , each having arms f^2 , to which are secured the oppositely-facing feelers f , so located as to coöperate with a released heddle-detector of one or the other harness-frame.

As shown in Fig. 5, the rock-shafts are provided with intermeshing segmental gears f' , and a spring s^{10} (shown only in Fig. 5) acts to move the feelers toward each other on their feeling stroke, the segmental gears insuring rocking of the rock-shafts f^x in unison, but in opposite directions.

The mechanism for operating the feelers and to cause the operation of the stopping instrumentality upon release of a detector will be described briefly hereinafter.

At each end of the back-stop and above the openings g^x the casting has secured to it vertically-adjustable brackets g^3 , each having a horizontal flat head g^4 and a depending foot g^5 , the feet supporting rods g^6 , which form warp-rests, one in front of and the other behind the two harness-frames H H' , only the front warp-rest being visible in Fig. 1. A vertical slot 22 in the bracket receives the shank of a clamping bolt 23, passed through and supported in the casting extended across the loom, one bolt serving for the pair of brackets at each end of the casting, and by means of the slots 22 the brackets can be adjusted vertically.

Each bracket-head g^4 has screwed into it a vertical stop g^{10} , shown as a screw-bolt and provided with a check-nut g^{12} , the head or upper end of the stop being located in the path of movement of the plunger-base extensions $e' e^2$ of the corresponding harness-frame—that is, each frame has one of the plungers at each side, as has been described, and there is a stop to coöperate with each plunger, this being clear from Figs. 1 and 2, and it will be evident that on the rise of a frame the expansion of the springs s^x will cause relative movement apart of the bars h^x and h'^x until the stops g^{10} are rendered inoperative by the rise of the frame. At such time the heddles will be hung or suspended from the main bars h^x and the lower edges of the auxiliary bars h'^x will be adjacent the bottoms of the heddle-slots d' , so that as the harness-frame is stopped at its upper limit of movement the tendency of the heddles to be thrown farther upward, due to momentum, will be prevented by the auxiliary bars. There is thus no straining of the warp from the jumping up of the heddles, and the latter are evened in their high position, making the strain equal upon the different warp-threads in the upper plane of the shed.

It should be stated at this point that the lateral enlargements 30 of the heads h^3 limit movement of the auxiliary bars away from the main heddle-bars h^x .

The shedding-cams C and C' are alike in contour and are shown as set opposite each other, and in Fig. 4 one of the cams is shown on an enlarged scale to more clearly illustrate

the construction thereof. The front harness-frame is up and stationary, while the treadle-roll t^x traverses the dwell portion from c to c' , Fig. 4, the jumping up of the heddles at the top of the stroke being prevented, as described, at the beginning of such dwell.

As the cam continues to rotate, however, the frame is depressed during the traverse of the treadle-roll from c' to c^3 on the shedding-cam, and as the short portion from c^2 to c^3 is concentric with its shaft the movement of the frame is stopped temporarily. Any tendency of the heddles to be thrown farther in a downward direction at this point is prevented by the main or upper heddle-support h^x , since the descent of the frame has been stopped temporarily, and the "auxiliary-bar" carriers, as the plungers e may be termed, are now in engagement with the vertically-adjustable stops g^{10} , so that the said auxiliary bars are at the end of their downward stroke.

Remembering that the main bars h^x are supporting the heddles, it will be manifest that such bars must descend farther in order to allow any heddles whose warp-threads are broken or unduly slack to drop into position to act as controller-detectors and detect the fault, although the intact threads must not be farther depressed. Consequently the cam from c^3 to c^4 is shaped to give a further depression to the harness-frame, moving downward the bars h^x while the auxiliary bars h'^x are held stationary by the stops g^{10} . Any released heddle can then move down, placing its lower end in the path of its coöperating feeler on the feeling stroke thereof, and by engaging and arresting the feeler the warp-stop-motion instrumentality is caused to operate and effect stoppage of the loom.

The heddles whose threads are intact are held down by the auxiliary bars h'^x , the strength of the springs s^x being sufficient to overcome or resist the upward strain of the warp-threads in the lower plane of the shed. From c^4 to c^5 the cam periphery is concentric, giving the dwell at the bottom of the stroke of the frame for detecting. Continuing the rotation of the cam after the dwell of the frame from c^4 to c^5 on the cam, the frame is raised quickly as the treadle-roll traverses the part $c^5 c^6$, which is the reverse of the part $c^3 c^4$, and the main bars h^x are then moved upward; but just as they take hold of the heddles at the upper ends of the slots d' the short dwell $c^6 c^7$ operates and prevents the heddles from being taken up with a jerk. By this time, however, the frame has risen far enough to permit the springs s^x to expand, and the carriers for the auxiliary bars h'^x are ready to rise from the stops g^{10} , the carriers being thereafter supported on the enlargements or shoulders 30, referred to. The main and auxiliary heddle-bars are now in normal relative position and rise in unison as the part $c^7 c$ of the cam coöperates with the treadle-roll, completing the rise of the frame.

Referring to Fig. 4, it will be seen that the

portion $c^3 c' c c^6$ is very similar to the ordinary cotton-harness shedding-cam, and it is the part of the cam which controls the motion of the heddles. While the portion $c^3 c^4$ 5 $c^5 c^6$ is in action the heddles are not moved, but rest upon the warp-threads and are held down by the auxiliary heddle-bar. Inasmuch as the position of the lower plane of the shed is the more important in adjusting harnesses, 10 I can with the mechanism herein shown adjust the harnesses for the upper plane of the shed with fair accuracy, and then by means of the adjustable stops g^{10} adjust the auxiliary bar with any degree of accuracy required 15 site to give good results. The lower plane of the shed is manifestly positioned by the auxiliary heddle-bar, so that the finer adjustment of the latter provides for the necessary accuracy.

20 I will now briefly describe the means whereby by the arrest of the feeler by a released heddle-detector releases the shipper S^X . Referring to Fig. 3, a knock-off arm k , adapted to engage the lower end of the shipper, is 25 mounted rigidly on a rock-shaft k^X , supported on the loom-frame and having a depending arm k' . A link K , Figs. 3 and 5, is pivotally connected at its lower end with said arm, the upper end of the link being hooked at k^2 , Fig. 30 5, to embrace the cam-shaft C^X , said link sustaining a short rock-shaft k^3 . The latter has fast upon it a rearwardly-extended arm k^4 , connected by a rod or link k^5 with an arm f^4 , fast on one of the feeler rock-shafts f^X , 35 and said rock-shaft k^3 has also a rigidly-attached follower k^6 and a bunter k^7 , the former being held in position to be engaged by a feeler-actuating cam K^5 , fast on the cam-shaft C^X . The spring s^{10} acts through the 40 link k^5 to keep the follower in co-operation with the cam K^5 , which is a double-throw cam, and the latter effects the non-feeling stroke of the feelers in a manner obvious to those skilled in the art. The bunter k^7 is located in the path of a cam having two oppositely-located tappets t^{10} , Fig. 5, and normally 45 the cam K^5 will operate through the follower to elevate the bunter and depress it without engagement by either tappet. When, however, 50 a released heddle engages a feeler, the latter is arrested on its feeling stroke, and the bunter k^7 will remain in the path of one or other tappet t^{10} , so that as the latter engages the bunter it will move it and the link K bodily to the left, Figs. 3 and 5, to thereby 55 turn the shaft k^X and act through the knock-off arm k to release the shipper S^X . Such release operates through any usual or suitable instrumentality—as, for instance, a belt-shifter—to stop the loom in order that the 60 fault may be remedied.

I have described briefly a simple and efficient form of mechanism for operating the feelers and for effecting shipper release when 65 a heddle released by failure or undue slackness of its warp-thread moves into position to engage and arrest a feeler; but any other

suitable mechanism of this general character may be employed so far as concerns the main features of my invention hereinbefore set forth.

Having fully described my invention, what I claim as new, and desire to secure by Letters Patent, is—

1. In a loom, a harness-frame positively controlling the position of the warp-eyes of the heddles during shedding, combined with a stopping instrumentality governed by or through the harness.

2. In a loom, a reciprocating harness-frame, means to control the movement thereof, heddles carried by the frame and each provided with a warp-eye, a stopping instrumentality caused to operate by or through a heddle upon failure of its warp-thread, and means to position the warp-eyes throughout shedding in conformity with the movement of the harness-frame.

3. In a loom, a shipper, a harness-frame provided with heddles having warp-eyes, means to positively control the position of the warp-eyes during shedding, and means to cause the release of the shipper by or through a heddle upon failure of its warp-thread.

4. In a loom, a reciprocating harness-frame, a series of heddles carried thereby and serving also as warp-stop-motion controlling-detectors, and means to positively control the position of the heddles during the formation of the shed.

5. In a loom, a harness-frame, a series of heddles carried thereby and having a limited longitudinal movement relative thereto, a cam to control the movement of the frame, and means to position said heddles in predetermined relation to the frame during the movement of the latter to form the shed.

6. In a loom, a reciprocating harness-frame, a series of heddles carried thereby and serving also as warp-stop-motion controlling-detectors, to effect the operation of a stopping instrumentality upon failure of a warp-thread, a shedding-cam, and means to positively control the position and movement of the heddles with relation to the harness-frame during the shed-forming movement of the latter.

7. In a loom, shed-forming mechanism, including harness-frames each provided with heddles serving also as controlling-detectors, intact warp-threads maintaining the heddles inoperative as detectors, and means to prevent movement of a released heddle into detecting position until after the shed is completed.

8. In a warp stop-motion for looms, heddles serving also as controlling-detectors, and means to permit a released heddle to drop into detecting position only after the shed is completed.

9. In a loom, harness-frames, heddles carried thereby and having limited longitudinal movement relative thereto to enable them to act as controlling-detectors for a warp stop-motion, means to reciprocate the harness-

frames, and means to prevent momentum-induced movement of the heddles when the proper shed-opening has been attained.

10. In a loom, harness-frames, heddles carried thereby and having limited longitudinal movement relative thereto to enable them to act as controlling-detectors for a warp stop-motion, means to move the harness-frames to form the shed, and means to prevent momentum-induced movement of the heddles when the frames have been positioned to properly open the shed.

11. In a loom, harness-frames, heddles carried thereby and having limited longitudinal movement relative thereto to enable them to act as controlling-detectors for a warp stop-motion, means to move the harness-frames to form the shed, and means to prevent continued movement of the heddles, due to momentum, when the harness-frames have opened the shed.

12. In a loom, a vertically-reciprocating frame having a cross-bar, a series of longitudinally-slotted heddles mounted on the bar and having a limited longitudinal movement relative thereto, and means independent of the bar to positively stop upward movement of the heddles when the harness-frame is at the upper end of its stroke.

13. In a loom, a vertically-reciprocating harness-frame, a series of heddles carried thereby and having a limited longitudinal movement relatively thereto, to enable the heddles to act also as warp-stop-motion controlling-detectors, a cam to control the reciprocation of the harness-frame, said cam causing the latter to diminish its speed before reaching the bottom of its stroke, and means to at such time stop descent of the heddles and thereafter to release the heddles from control thereby.

14. In a loom, a vertically-reciprocating harness-frame having transverse main and auxiliary heddle-supports one of which is movable toward and from the other, a series of heddles serving also as controlling-detectors and longitudinally slotted to receive said supports, means to reciprocate the frame, and means to stop the movable support before the harness-frame has completed its stroke.

15. In a loom, a vertically-reciprocating harness-frame having a rigidly-connected main heddle-bar, an auxiliary heddle-bar below and movable toward and from the main bar, a series of heddles serving also as controlling-detectors and longitudinally slotted to receive

said bars, spring-controlled carriers for the auxiliary bar, and means to stop the movement of the latter at a predetermined point in the downward stroke of the harness-frame.

16. In a loom, a vertically-reciprocating harness-frame having transverse main and auxiliary heddle-supports one of which is movable toward and from the other, a series of heddles serving also as controlling-detectors and longitudinally slotted to receive said supports, means to reciprocate the frame, and vertically-adjustable means to stop the movable support at a predetermined point in the downward stroke of the harness-frame.

17. In a loom, a vertically-reciprocating harness-frame having a rigidly-connected main heddle-bar, an auxiliary heddle-bar below and movable toward and from the main bar, a series of heddles serving also as controlling-detectors and longitudinally slotted to receive said bars, means to maintain the bars relatively immovable as the harness-frame reaches the upper end of its stroke, the auxiliary bar then acting to prevent jumping up of the heddles, and stops to engage and hold the auxiliary bar stationary at a predetermined point on the downward stroke of the harness-frame, continued movement of the latter causing the main and auxiliary bars to approach each other and permit a heddle released by failure or undue slackness of its warp-thread to drop into detecting position.

18. In a loom, a vertically-reciprocating harness-frame, a series of heddles carried thereby and having a limited longitudinal movement relatively thereto, to enable the heddles to act also as warp-stop-motion controlling-detectors, means to prevent such relative movement until shedding is completed, and means to control the reciprocation of the harness-frame, said latter means causing the harness-frame to diminish its speed before shedding is completed.

19. In a loom, a vertically-reciprocating harness-frame having a heddle-bar movable with relation thereto, and adjustable means independent of said frame to set the bar in proper position for an open shed.

In testimony whereof I have signed my name to this specification in the presence of two subscribing witnesses.
